COIN CHUTE

William Patzer, Chicago, Ill., assignor to A. B. T. Manufacturing Corp., Chicago, Ill., a corporation of Illinois

Application April 20, 1938, Serial No. 203,026

5 Claims. (Cl. 194—97)

This invention pertains to coin testing devices and has as one of its principal objects the provision of improved testing means for stopping deformed and bent coin elements in coin chutes and the like.

A further object is the provision of testing means for arresting bent coin elements and effecting release of such elements in a manner to prevent their continued passage through the chute as a result of fraudulent manipulation of the testing means.

Another object is the provision in a coin chute of a movable chute section and means for moving the same out of alignment with a main chute passage to a discharge position for the purpose of ejecting a bent coin or the like arrested in the movable section and assuring positively that such coin cannot continue its passage down the chute upon discharge.

Another object is the provision of a movable chute section comprising a pair of spaced plates one of which is movably carried on the other, the same being normally in a predetermined relative position to provide a coin passage of fixed width suitable to stop a bent coin element, but permitting passage of a proper coin element therebetween, together with means for moving the movable section out of alignment with the main chute passage and separating the relatively movable plate members to widen the distance therebetween and free the bent coin element.

Still another object is the provision of a movable chute section comprising a pair of spaced plates, one movably mounted on the other, and spaced so as to form a constriction adequate to stop a bent coin element, but not a proper coin element, and means for moving the pair of plates constituting the movable section out of alignment with the main chute section and effecting a separating movement of the two plates during this action, so that any bent coin element lodged therebetween will be free to gravitate therefrom.

Yet another object is the provision in a testing device of the class heretofore characterized of a magnetically attractable feeler arranged for cooperation with the movable chute section for the purpose of arresting coin elements having irregular facial contours or perforations.

Other objects reside in the form, construction, arrangement and operation of the parts and mechanism for accomplishing the foregoing objects, together with other features of novelty, all of which will appear more particularly as the

following description proceeds in view of the drawing, in which:

Fig. 1 is a side elevation of a chute embodying the novel testing means;

Fig. 2 is a fragmentary side view of the testing means as seen from the opposite side of the chute of Fig. 1;

Fig. 3 is an enlarged vertical section along line 3—3 of Fig. 1;

Fig. 4 is an enlarged fragmentary vertical section similar to Fig. 3, showing the testing apparatus in discharge position;

Fig. 5 is a perspective view of the companion plate member of the movable chute section;

Fig. 6 is a perspective of the opposite side of the companion plate of Fig. 5;

Fig. 7 is a fragmentary perspective view of the upper left-hand side of the coin chute as seen in Fig. 1.

The present invention provides improvements in a type of coin chute or testing device described in a copending United States Patent No. 2,233,654 dated March 4, 1941.

Such a coin chute includes a main chute body 10 (Fig. 1) preferably constructed by assembling a pair of cast side plates 11 and 12 (Fig. 3), the plates having formations on their confronting surfaces providing a tortuous and descending chute passage 13 (Fig. 1) having an entrance opening 14 at its upper end, and a plurality of discharge openings 15 and 16 at its lower end.

Between the entrance 14 and the discharge openings in the chute, there are provided various testing means including a rebound anvil 20 in the upper portions of the chute passage just above a sidewise discharge opening 21 through which lightweight and undersized tokens may pass sidewise out of the chute and down a discharge ramp 22 formed on the outside of one of the body plates 12 as a part of the casting, there being a cover plate 23 secured over the ramp portions 22 by means such as the screws 24 so that there is thus formed what may be termed an external or outside discharge passage which terminates at its lower end 25 alongside the reject discharge opening 16 of the main chute passage. At its upper end 26, this external discharge chute is open to receive ejected coin elements from the special testing means which constitutes one of the principal features of the present invention, as will hereinafter be described.

Arranged below the sidewise discharge or drop-out opening 21 is a magnetic testing means in the form of a pair of permanent magnets 30 se-

cured by means of straps 31 to the opposite sides of the main chute body with their pole pieces arranged so as to create a magnetic flux across the main coin passage 13 for the purpose of arresting magnetically attractable elements which may descend that far in the chute, and also for the purpose of affecting the rate of movement of various coin elements preparatory to their encountering a further testing means in the form of adjustable rebound or deflecting members 32 and 33 arranged in the main chute passage below the magnetic means 30 and above the main discharge openings 15 and 16.

The testing means 32 and 33 have knife edges or points 32' and 33' which are engaged variously by different kinds of coin elements subsequent to being influenced by the magnetic means 30 so as to guide such coin elements into one or the other of the discharge openings 15 or 16 dependent upon the physical characteristics of the coin elements and whether or not they are of a type which the testing means is adapted to accept or reject, the opening 16 constituting a reject opening and the opening 15 constituting an acceptance passage which communicates with a coin drawer or other receiver (not shown).

Ordinarily, coin elements deposited in the opening 14 travel down the passage 13 and strike the anvil 20, and if their characteristics are proper they will bound sufficiently to carry them past the sidewise drop-out opening 21. Should such coin elements be of improper physical characteristics, for example, if they are made of lead, paper, or material other than that of an acceptable coin, the likelihood is very great that they will drop into the opening 21 and into the external discharge chute 23 to gravitate out the discharge opening 25.

If the coin elements succeed in passing the opening 21, they continue on down the chute and, assuming they are formed of metallic material, their rate of movement will be slowed up by the magnetic testing means 30, proper coin elements being affected in a particular manner by this latter testing means so as to move between the testing devices 32 and 33 and out the acceptance opening 15, whereas improper coin elements will engage one or both of the testing devices 32 and 33 in a manner to be deflected into the discharge opening 16.

The novel testing means of the present invention is arranged in the upper portions of the chute and is particularly effective to arrest bent or deformed coin elements which, in the absence of such an arresting means, are very likely to descend into the lower regions of the coin passage and become wedged therein and put the device out of operation.

In a preferred embodiment of the arrangement, the main chute is provided with a movable passage section including a main gate 35 (Figs. 1 and 3) mounted for pivotal movement about a horizontal axis on a pintle 36 extended between a pair of ears 37 forming a part of the side plate 11 at its upper end, the gate 35 thus being adapted to swing from a normal position wherein it is substantially flush with the main side plate 12, as in Fig. 3, into an offset position away from the chute, wherein it is out of alignment with the main chute passage, as seen in Fig. 4.

Attention is called to the fact that the main gate 35 has a pair of offset ears 38 and 39 at its upper end apertured to receive the pintle 36, the clearance between the pintle 36 and the aperture in the ear 38 being normal, that is, a relatively

close fit, so that that portion of the gate 35 tends to pivot properly in the usual manner on the pintle 36; however, the opposite ear 39 of the main gate 35 is provided with an elongated slot 40 (Figs. 3 and 4) which permits the gate to shift laterally of the pintle upon application of force in a proper direction to that side of the plate, this movement being illustrated in the different positions of the gate shown in Figs. 3 and 4.

Yieldable means normally urging the main gate 35 into an initial position flush against the side of the chute as illustrated in Fig. 3, includes a coil spring 44 mounted on a headed pin 45 which extends freely through an opening 46 in the gate and is anchored in the opposite side plate 11 so that the gate must bear against the spring 44 in moving into open position. At the opposite side of the main gate 35 there is a similar spring means 47 near the lower marginal portion of the gate. When the gate is in its normal position seen in Fig. 3, it will be observed that the shifting ear 39 thereof is urged to its inward limit against the pintle 36.

Means for effecting opening and closing movement of the gate 35 includes a lever 50 pivotally mounted as at 51 on a bracket suitably attached to the chute body and having an upper end portion arranged to bear against a lug 52 extending from an offset ear 53 on the main gate, the arrangement being such that when the lever is pivoted to cause its upper end portion to bear against the lug 52, as illustrated in Fig. 4, the main gate 35 will be pivoted out of its normal position and out of alignment with the main chute passage.

Completing the movable passage section is a companion plate 55 (see also Figs. 5 and 6) which is yieldably mounted on the main gate by means extending through ears 56 and 58 (Fig. 2) in the companion plate so as to hold the latter in a normal position with respect to the main gate 35 and thereby provide a passage. A pin means 57 provided with a spring 57' similar to the springs means 44-45 of Fig. 3 is provided for each of the ears 56 and 58 to mount the companion plate 55 for floating movement on the main gate, thus permitting a limited degree of movement between the companion plate and the main gate.

The companion plate 55 has an inwardly offset section 59 (Fig. 5), from a vertical edge portion of which extends a pair of ears 60 each apertured to receive headed pin means 61 extending freely through the main gate into the companion plate, there being coil springs 62 between the headed portions of the pins 61 and the main gate which tend to draw the companion plate to the limit of its inward movement against the main gate, thus disposing the offset section 59 in a normal spaced position at a predetermined distance from the main gate, which distance is calculated to permit the passage between the offset section 59 and opposite portions of the main gate or plate 35 of proper coin elements, bent coin elements becoming wedged between the offset portion 59 and the main gate so that their progress down the chute is arrested.

By proper manipulation of the scavenging lever 50, the main gate may be swung into the discharge position of Fig. 4 so as to move the coin passage formed between the same and the companion plate 55 out of alignment with the main coin passage 13.

A particular feature of the invention resides in the fact that the foregoing arrangement permits the upper end of the movable chute passage section to be thrown out of alignment slightly in advance of the lower end thereof by virtue of the shiftable mounting of the ear 39 on the pintle 36, the arrangement being such that as soon as an outwardly directed effort is applied to the lug 52 (Figs. 1, 3, 4), the end of the main gate nearest the lever 50 is shifted laterally of the pintle 36 against the compression of the spring 44; and as soon as this lateral shifting is completed (occurring very rapidly), the main gate begins pivotal movement relative to the pintle 36 with further compression of the spring 44 on pin 45 and the spring (not shown) on the lower pin 41.

During the aforesaid initial movement of the main gate, the companion plate 55 does not move relative to the main plate member, so that a bent coin wedged in the movable passage section constituted by these plate members is not dislodged during the initial movement of the gate but is moved out of alignment with the main coin passage 13.

Substantially at the time the main movable chute section or gate 35 begins its positive pivotal movement on the pintle 36, the companion plate member 55 is caused to separate from the main gate member by virtue of the provision of an offset lug 65 (Fig. 6) on the back or outer side of the offset section 59 of the companion plate. This lug 65 is positioned to move into a slot 66 cut in the main chute plate 11 adjacent the margin of an opening cast therein and through which the plate 55 moves. The initial outward movement of the main gate plate 35 causes movement therewith of the companion plate, and substantially at the time the main gate begins its proper pivotal movement (as distinguished from shifting) the offset lug 65 is urged against the bottom of the slot 66 so that further movement of the companion plate with the main plate is prevented at that end of the companion plate where the lug 65 is mounted, it being recalled that the spring means 62 yielding-ly attach the vertical edge portion of the companion plate nearest the lug 65 to the main gate. Moreover, it will be recalled that the pin means 57 which attaches the companion plate to the main gate is also provided with spring means 57' similar to the means 62.

Thus, it will appear that after the main gate 35 moves a predetermined distance toward open position, the companion plate 55 is prevented from following with the main gate by the lug 65, with the result that the main gate continues its outward movement and thus separates from the companion plate, widening the space therebetween and freeing a bent coin element wedged therebetween, the lower end of the companion plate, however, tending to follow the main plate due to its rigid connection at the ear 56, and hence throwing the lower end of the companion plate farther out of alignment with the main chute passage than the upper end. This arrangement assures that when the bent coin element is freed by such separation of the plates constituting the movable passage section, the lower end of this movable passage section, and particularly the lower end of the companion plate, will be thrown far enough out of alignment with the main chute passage so that it will be impossible to continue its passage on down the chute, such coin element being positively guided

5 for gravitating movement sidewise out of the main chute into the external discharge ramp or passage 23 for ultimate discharge from the opening 25 thereof.

Additional testing means includes a permanent bar magnet 70 (Fig. 2) mounted on a strap 71 on the main body plate 11 by means of screws 72 extending into the latter, the magnet being disposed with its length extending sidewise parallel to the main chute passage just below the entrance 14, it being observed that an appreciable portion of the magnet 70 lies behind the offset portion 59 of the companion gate plate. This gate plate is preferably made from a non-magnetic but electro-conductive material, such as hardened copper or phosphor bronze, so that the companion plate will have a degree of resiliency of its own to further expedite throwing the lower end thereof out of alignment, the electro-conductive characteristic thereof being useful in affecting the movement of coin elements therewith due to eddy currents set up by the magnet 70 in the coin and plate 55.

25 Cooperating with the last-mentioned magnetic testing means is a feeler of magnetically attractive wire or the like clamped between its end portions in a pivoted clip 75 arranged to pivot on a pin 75' carried by and extending from a small lug 76 attached to the main gate plate, the feeler having a lower end portion 77 attracted by the magnet 70 through an upper sidewise drop-out opening 78 formed in the main gate plate and extending in a descending sense laterally with the adjoining chute passage, this opening 78 being slightly less in width than the diameter of a proper coin, so that coin elements of less than a predetermined diameter will drop sidewise out of the movable chute passage section into the external discharge ramp, the floor of the chute passage underlying the movable chute section particularly opposite the opening 78 being pitched to facilitate such sidewise discharge movement of a coin element.

35 The lower end portion 77 of the feeler is attracted by the magnet 70 against the offset surface 59 of the companion gate plate at a point close to the upper end of the drop-out opening 78, while the upper end 79 of the feeler lies behind an arm 80. The arm 80 has its right end portion (Fig. 1) disposed through an aperture 80' formed in the main gate plate 35 and is fixedly attached to the plate 11 to provide an abutment against which the upper end of the feeler bears when the movable passage section is open, with the result that the feeler is pivoted away from the offset surface 59 of the companion plate to release any apertured or other irregular coin element into which the feeler has engaged as a result of its attraction by the magnet 70. Not only is the foregoing arrangement of the feeler and offset plate portion 59 effective to arrest apertured coin elements but many coin elements having unusual irregularities in surface configuration, such as variously inscribed or engraved tokens, are likewise effectively stopped by the feeler to be ejected when the main gate is opened as aforesaid.

40 A preferred form of the invention has been described in detail for purposes of illustration, and it will be appreciated that the numerous objects and advantages of the invention may be accomplished by other forms of construction and functional arrangements of the parts without departing from the spirit of the invention 45 which is therefore not limited by any specific

detail of form, location or operation of the coin testing means hereinbefore described, except as may be expressly provided in the appended claims.

Having thus described my invention, what I claim as new and desire to protect by Letters Patent is:

1. In a coin chute, means providing a stationary portion having a coin passage formed therein, and having a moveable passage section comprising a pair of opposite wall members mounted for joint movement into and out of alignment with the stationary portion of said coin chute, one of said moveable wall members having an opening formed therein, a magnetically attractive feeler mounted on said one of said moveable wall members for movement to project an end portion through said opening in said wall member in a direction across said moveable passage toward the remaining wall portion of the moveable section, magnetic means arranged on said stationary portion in the region of said remaining wall portion to attract the end of the feeler toward the same as aforesaid, coin elements moving in said passage between said wall portions engaging said feeler and moving the same so that said end portion bears against a side of the coin element, said end portion of the feeler engaging the surface formations on certain coin elements to arrest the same, means for effecting movement of said moveable passage section out of normally aligned position, and means coacting with said feeler to effect substantial withdrawal of the same from said moveable passage section when the latter is moved a predetermined amount out of normally aligned position whereby to release an arrested coin element for movement out of said moveable passage section when the same has been moved a predetermined amount out of alignment.

2. In a coin chute, the combination with a relatively stationary passage section of a moveable passage section normally disposed in alignment therewith, means mounting said moveable passage section for pivotal movement into and out of alignment with said stationary section, means forming a part of said mounting means of said moveable passage section and permitting lateral movement of said moveable passage section in advance of pivotal movement thereof, means for effecting movement of said moveable passage section, means on the latter adapted to be engaged by said means for effecting pivotal and lateral movement of the moveable passage section for the purpose aforesaid, said moveable section carrying a companion plate, means mounting said companion plate on said moveable section for lateral movement relative thereto and for normally holding the same in spaced relation with respect thereto, and means on said companion plate and normally out of engagement with said stationary passage section and adapted to engage the latter when the moveable section has been pivoted as aforesaid to effect lateral movement of said companion plate whereby arrested coins will be freed for gravitation out of said moveable passage section.

3. In a coin chute, a stationary portion providing a fixed coin passage, a gate member and a companion plate mounted thereon providing a moveable passage normally aligned with said fixed passage, means for effecting movement of said gate member out of alignment with said stationary portion, said gate member being arranged on said stationary portion with a particular part disposed near said moving means adapted to be

5 moved out of alignment in advance of the remaining portions of said gate, an opening formed in the gate, a feeler pendently supported on said gate and having a magnetically attracted end portion extending through said opening in said gate across the moveable passage, magnetic means arranged on the stationary portion adjacent the companion plate in a position to attract said end portion of the feeler toward the 10 companion plate, said feeler yielding to contact by certain coin elements to permit the latter to travel through the moveable passage with the end portion of the feeler bearing against the side of the coin to engage formations thereon as a result 15 of the aforesaid attraction, said feeler having an opposite end portion extending radially of said pendant support, and means mounted on said stationary portion adapted to be engaged by said radial extension of the feeler to effect substantial withdrawal of said magnetically attracted end portion out of said moveable passage when the latter is moved a predetermined amount out of alignment to release an arrested coin during 20 the aforesaid advance movement of said gate member.

4. In a coin chute, means providing a descending coin passage having an entrance at its upper end and an exit at its lower end and a movable passage section between said ends, said movable passage section including a pair of normally spaced wall sections defining a passage portion therebetween and arranged and mounted for joint movement to dispose said passage portion out of a normal condition of alignment with respect to the remaining portions of the coin passage, one of said wall sections being movable relative to the other to widen said movable passage section, means for effecting movement of the movable passage section out of aligned condition as aforesaid, said movable section being mounted with one end disposed near said entrance and means for moving said end a predetermined amount out of alignment in advance of the remaining portions of the movable passage section, and means for effecting movement of the movable wall section of said pair away from the other during the aforesaid advance movement of the movable passage section.

5. In a coin chute, the combination with a relatively stationary passage section of means providing a moveable passage section normally aligned with said stationary passage section and including opposite wall members and means mounting the same for joint movement and for movement relative to each other from a normally spaced relationship to widen the passage portion defined therebetween, means for jointly moving said wall members out of alignment with said stationary passage section, means cooperating 50 with one of said wall members for restraining the same from movement in and out of normally aligned condition when said wall members are moved jointly a predetermined amount, said one of said wall members having a lug portion adapted to engage the stationary passage section when said wall sections are moved a predetermined amount, whereby to widen portions of said moveable passage section to facilitate release of arrested coins, and magnetic means mounted on said stationary section in a position so as to be cooperably related to said moveable section to influence the movement of coins therein when the section is in normally aligned condition, feeler means pivotally mounted on said moveable pas-

sage section and having a lower end portion thereof pendently disposed within said movable passage and adapted to be attracted by said magnetic means, said feeler means having an opposite end extending upwardly and adapted to engage said stationary passage section to pivot said lower end portion in a direction away from said

movable passage when said opposite wall members are moved to widen portions of said movable passage as aforesaid and arranged to release arrested coins when said movable section is moved a predetermined amount out of normally aligned condition.

WILLIAM PATZER.
